A. VROBLE

CURTAIN SUPPORT

Filed Feb. 17, 1923

Patented Feb. 10, 1925.

1,525,477

UNITED STATES PATENT OFFICE.

ALEXANDER VROBLE, OF DETROIT, MICHIGAN.

CURTAIN SUPPORT.

Application filed February 17, 1923. Serial No. 619,633.

To all whom it may concern:

Be it known that I, ALEXANDER VROBLE, a citizen of the United States, residing at Detroit, in the county of Wayne and State 5 of Michigan, have invented a new and useful Improvement in a Curtain Support, of which the following is a specification.

My invention relates to a new and useful improvement in a curtain support and has 10 for its object the provision of a curtain support which will be simple in structure economical of manufacture and highly efficient in use.

The invention is designed to afford a curtain support which may be raised and lowered to suit the convenience of a person removing a curtain therefrom or putting one thereon, to eliminate the necessity of the use of a raised support or ladder for 15 the person to stand on while changing the curtain and has for a further object the provision in such a device of means for easily and quickly raising the curtain, when placed thereon, to its proper position and turning 20 the edges of said curtain around the corner 25 of the support.

Other objects will appear hereinafter.

The invention consists in the combination and arrangement of parts hereinafter described and claimed and will be best understood from a reference to the accompanying drawings which form a part of this specification and in which,

Fig. 1 is a front elevational view of the invention applied to a window,

Fig. 2 is a side elevational view of the invention, and,

Fig. 3 is a top plan view of the invention.

The invention in its preferred form is 40 described herein, although it will appear apparent, as the description proceeds that many changes may be made in the details by a skilled mechanic working in the art and these various modifications I wish to 45 embrace although not shown herein but embraced in the appended claims.

Mounted on the window frame 9, at opposite sides of the window, are roller supporting members 10, having an angularly 50 turned portion 11 and provided with openings for the reception of the ends of a shade roller 12 on which is mounted a shade 13, one of said supporting members having a slot formed therein and the other a round 55 opening for the reception of the pin which supports the roller at one end, the slot serv-

ing to receive and prevent the turning of the pin which is attached to the roller spring. Adjacent the end of the supporting members is a slot 14 which communicates with a slot 15 formed in said member at an angle to the slot 14. These slots are formed in both of the supporting members, so that it is possible to use a shade roller therewith which is adapted to turn either 60 direction. Mounted in the slot 15 is a shade roller 16 carrying the shade 17 in the conventional manner, said roller being equipped with a spring for rolling the same 65 in the ordinary manner. The free end of the shade 17 is doubled upon itself to form a sleeve in which is positioned a supporting rod 18 projecting from each end of which is a rod or pin 19 having an enlarged head 20. Made of sections adapted to telescope 70 in the ordinary manner of curtain rods is a rod 21, at each end of which is pivotally mounted an arm 22, the end of the rod 21 being preferably bifurcated and the arm held in pivotal relation thereto by a suitable 75 bolt or rivet. The arm or link 22 is provided adjacent its free end with an enlarged opening 23 which communicates through a neck or restricted opening 24 with a smaller opening 25. The head of the pin 19 is 80 thrust through the enlarged opening in the link and then the pin is moved rearwardly to the small opening so that the head 20 prevents a withdrawal of the pin 19 from the link. A cord 26 is attached to an eye 85 screw 26' which is threaded through the shade 17 into the stick or support 18, thus preventing any longitudinal movement of the member 18 in the sleeve and at the same 90 time affording a means for unwinding the shade 17.

When it is desired to place a curtain on the support 18 the shade 17 is unwound until the person placing the curtain on the support can easily reach it from the floor. 100 It will be noted from Fig. 1 that the member 18 then supports the member 21 which hangs on the links 22 which extend vertically. The curtain upon being placed on the member 21, is looped over the ends of the links 22. After the curtain is placed on the rod 21 the shade 17 is then rolled on the roller until the member 18 is carried into the position shown in Fig. 3, the pins 19 105 engaging the upper edge of the supports 10. It will be noted that the shade 17 rolls down in front of the roller, which is the 110

reverse of the action of the ordinary window shade roller. By rolling this shade in this manner the member 18 is carried rearwardly over the top of the roller so as to bring the 5 links 22 into a horizontal position, thus forming the upper edge of the curtain into a U-shaped form with an elongated bight, and thus presenting the appearance desired in hanging curtains in the usual manner.

10 The manner of mounting the curtain is apparent from Fig. 1 in which the curtain is shown in dotted lines. It will be noted that the pins 19, intermediate their ends are provided with a flattened portion 28, so that 15 if the shade roller 18 should become disarranged the curtain may be supported temporarily by the member 18, which would first be removed from the sleeve of the shade. The curtain rod 21 would still be used in 20 this case.

While I have illustrated and described the preferred form of structure I do not wish to limit myself to the precise form of structure shown but desire to avail myself of 25 such variations and modifications as come within the scope of the appended claims.

Having thus described my invention what I claim as new and desire to secure by Letters Patent is:

30 1. A movable curtain support comprising a supporting member adapted for raising and lowering relatively to its position of mounting; a curtain supporting member mounted thereon; and means, at opposite 35 sides of said curtain supporting member, extending angularly thereto and adapted for lying in horizontal position when in raised position and vertically when in lowered position, said means being adapted, when 40 in horizontal position, for retaining said curtain in forwardly extended position relatively to said supporting member.

2. A movable curtain support adapted for mounting on a shade roller, comprising a supporting stick; a curtain supporting rod; means for pivotally connecting said supporting rod to said supporting stick, said means being adapted for lying in horizontal position upon the raising of said curtain to operative position for retaining said curtain normally in forwardly spaced position 45 relatively to said shade roller.

3. In combination with a shade roller and a bracket for supporting the same, a supporting member mounted on the free end of 50 said shade roller; a curtain supporting rod; links connected to said curtain supporting rod; and means projecting from said links to said supporting member adapted, upon the rolling of said shade, for engaging the 55 upper surface of said brackets, said links being adapted, upon the engagement of said means with said brackets for lying in horizontal position for retaining said curtain supporting rod in parallel relation to and 60 spaced from said supporting member.

4. A device of the class described, comprising a shade roller; brackets for supporting said shade roller; a supporting stick mounted on the free end of said shade roller; 70 trunnions projecting outwardly from the opposite ends of said stick; links mounted on said trunnions; a rod mounted on said links, said trunnions being adapted for engaging the upper surfaces of said brackets 75 upon the rolling of said roller, said trunnions being disposed in horizontal position upon the engagement of said trunnions with said brackets.

In testimony whereof I have signed the 80 foregoing specification at Detroit, in the county of Wayne and State of Michigan.

ALEXANDER VROBLE.
